UNITED STATES PATENT OFFICE.

BYRON E. VIELE, OF GRINNELL, IOWA.

TURNTABLE.

1,355,722.

Specification of Letters Patent. Patented Oct. 12, 1920.

Application filed July 29, 1919. Serial No. 314,111.

To all whom it may concern:

Be it known that I, BYRON E. VIELE, a citizen of the United States, residing at Grinnell, in the county of Poweshiek and State of Iowa, have invented certain new and useful Improvements in Turntables; and I do hereby declare the following to be a full, clear, and exact description of the invention, such as will enable others skilled in the art to which it appertains to make and use the same.

My invention relates to improvements in turntables especially adapted for use in roundhouses in directing locomotives to different points in the roundhouse.

An important object of this invention is to provide an apparatus of the character described having means carried by the turntable to rotate the same.

20 A further object of the invention is to provide a turntable mounted on a centrally disposed pivot and having connection with a single wheel operating on a circular track, said wheel being adapted to be rotated, to 25 in turn rotate the apparatus.

A further object of the invention is to provide a device of the character described which is efficient in use, simple to operate and of highly simplified construction.

30 Other objects and advantages of the invention will be apparent during the course of the following description.

In the accompanying drawings, forming a part of this specification, and in which 35 like numerals are employed to designate like parts throughout the same,

Figure 1 is a vertical longitudinal section, taken through the apparatus,

Fig. 2 is a front elevation of the propelling wheel of the turntable, showing the 40 same journaled through a slotted bearing,

Fig. 3 is a plan view of a turntable embodying my invention,

Fig. 4 is a plan view of a turntable embodying my invention, parts thereof being 45 broken away, and

Fig. 5 is a plan view of a portion of the propeller mechanism.

In the drawings, wherein for the purpose 50 of illustration, is shown the preferred embodiment of my invention, the numeral 10 designates a circular pit having a base 11 disposed centrally thereof and supporting a pivot 12. A turntable, generically designated by the numeral 13, is rotatably mounted on the pivot 12 and is comprised of a

stout frame 14 and a horizontal structure 15, having rails 17 upon its upper surface.

A circular track 18, arranged in the pit 10, and disposed beneath the turntable 13, 60 is mounted on a base 19 within the pit 10.

The turntable carries a motor 20, which may be of any desired type, and is adapted to cause the turntable to partake of a rotary movement.

A connecting rod 21, extending 65 from the motor 20, is secured to a crank 22 disposed at right angles to the motor 20.

A bevel gear 22' is disposed on one end of the crank shaft 22 and has engagement with a second bevel gear 23.

The crank shaft 22 70 operates in bearing members 24, which may be of any suitable type.

A shaft 25, extending longitudinally of the turntable is connected with the bevel gear 23 and has ar-

ranged on its opposite ends a wheel 26, 75 adapted to partake of engagement with the circular track 18.

The inner end portion of the longitudinally extending shaft is journaled in a bearing member 27, while the outer end portion thereof is journaled

through a reciprocating bearing member 28 80 arranged in a box 29. A spring 30 serves to

normally hold the shaft 25 in a horizontal position.

Elongated openings 31, extending 85 vertically of the bearing box 29, permit

of the shaft 25 partaking of a reciprocating movement.

As clearly shown in Fig. 5, the bearing box 29 is secured to the side of the turntable, as at 32. Particular attention is

called to the fact that the spring 30 serves 90 to retain the wheel 26 firmly in contact with the circular rail 18.

In practice, the motor 20 may be of the steam type, and it will be apparent that by connecting the motor with

the locomotive on the turntable, it will be 95 unnecessary to maintain a separate boiler for the motor.

The operation of my improved turntable is as follows:

A locomotive is run on the tracks 17 un-

der its own power if possible. To rotate 100 the turntable to the desired point, the motor 20 is operated, which in turn operates the

wheel 26, having engagement with the tracks 18.

It will be thus apparent that the travel 105 of the wheel 26 will cause the turntable to

partake of a rotary movement in the desired direction.

With reference to Fig. 1 it will be seen 110 that the wheel 26 is forced into firm contact with the circular tracks 18 by the weight of the turntable and the spring 30.

While I have shown and described the

preferred embodiment of my invention, it is understood that I may make such minor changes in arrangement and construction of parts as will remain within the spirit of the 5 invention and the appended claim.

Having thus described my invention, what I claim is:

A turn table comprising a pivot member mounted in a pit, a table pivoted upon the 10 pivot member, a circular track located in the pit below the table, a motor fixed to the table, a shaft journaled upon the table, transmission means operatively connecting the motor with the shaft and carried by the 15 table, a bearing member fixed to the table, a

bearing movably mounted in the bearing member, a spring interposed between the bearing member and the bearing and serving to hold the bearing in a lowered position in the bearing member, said bearing 20 receiving the shaft and a wheel mounted upon the shaft and adapted to travel upon the track.

In testimony whereof I affix my signature in presence of two witnesses.

BYRON E. VIELE.
